UNITED STATES PATENT OFFICE.

ANDREW A. SMITH, OF CRESTED BUTTE, COLORADO, ASSIGNOR OF ONE-HALF
TO E. A. PRAY, OF SAME PLACE.

SPRAYING CAR-WHEEL AND SPRAYING-BAR.

SPECIFICATION forming part of Letters Patent No. 312,028, dated February 10, 1885.

Application filed December 8, 1883. Renewed December 16, 1884. (No model.)

To all whom it may concern:

Be it known that I, ANDREW A. SMITH, a citizen of the United States, residing at Crested Butte, in the county of Gunnison and State of Colorado, have invented a new and Improved 5 Spraying Car-Wheel and Spraying-Bar, of which the following, in connection with the annexed drawings and the letters of reference thereon, is a specification.

My invention is intended to overcome the inconvenience, avoid the frequent loss of life or limb, and save much of the expense now experienced with the use of ordinary "spraying-pins" on coal-cars running over inclined 15 planes or downgrade roads. With the old mode of "spraying" a coal-car on an inclined or downgrade road it is customary to provide a number of strong wooden pins sharpened at both ends, and the "sprayman" or person 20 who attends to the running out of the cars runs alongside the train and places a spraying-pin between the spokes of each of the wheels of a car, and said pins lock or arrest the revolution of the wheels, and thereby cause the 25 speed of the train to be slackened, the pins by thus locking the wheels causing them to slide with great friction upon the track; and in case it is not desired to stop the train entirely, the sprayman runs alongside the same and at the 30 desired moment pulls out the spraying-pins, which operation is often attended with loss of life or limb, it requiring to be performed while the train is moving, and there being a liability of his slipping and falling in a position where the 35 train may run over him, a casualty which has often occurred. The expense for the wooden spraying-pins, owing to their rapid wearing out or frequent breakage and getting lost, is very considerable, it rising as high as from three 40 dollars to three dollars and fifty cents for one car in a year, and the demand for these spraying-pins is so extensive in coal-region sections of the country that they are shipped as an article of trade by the car-load to the consumers. 45

My invention consists, first, in the combination, with a spraying car-wheel provided with spraying teeth or pins, of a vibrating spraying-bar applied upon a car, and adapted for working in connection with the teeth or pins formed on the spraying car-wheels, whereby the car-

wheels can be stopped or started in their revolution in an instant, and the speed of the car caused to be either slackened or accelerated without using ordinary spray-pins or endangering the life of the attendant. 55

It consists, second, in a vibrating spray-bar applied upon a car, in combination with two pairs of spraying car-wheels, each pair being provided with spraying-teeth of reverse construction, whereby a front wheel on either side of a car and a rear wheel on either side thereof, accordingly as the car may be turned around, can be simultaneously sprayed, and thus both the front and rear pairs of wheels 65 locked simultaneously by the attendant from either side of the car.

It consists, third, in a vibrating spray-bar provided with stop-lugs and an extension handle or handles, whereby the bar can be readily 7c operated by an attendant from a position on the ground.

In the accompanying drawings, Figure 1 is a perspective view of a coal-car body provided with my new spraying car-wheels and new 75 spray-bar. Fig. 2 is an inverted plan view of the same. Fig. 3 is a perspective view of a modified form of the spraying car-wheel. Fig. 4 is an inverted plan of a coal-car, spray-bar, and another modified form of car-wheel; and 80 Fig. 5 is an elevation of one of the car-wheels shown in Fig. 4.

In the drawings above described, A is a coal-car body, B B its axles, and C C' front and rear car-wheels, and D the spray-bar, pivoted 85 at a to the under side of the car-body, as shown. The car-wheels are formed with either a ratchet-toothed tread portion, e, as in Fig. 1, or with a ratchet-toothed flanged portion, as in Fig. 3, or with strong pins projecting 90 from their inner faces, as shown in Figs. 4 and 5. The spray-bar at each of its ends is formed with front and rear spraying-lugs, d, and handle-extensions d', which latter extend out beyond the outer faces of the wheels, so that 95 they may be grasped by the attendant without endangering his life or limbs. The lugs d are situated so as to stand between front and rear wheels when the spray-bar lies at right angles to the sides of the car-body, and so as 100 to come under the shoulders of the ratchet when such bar lies slightly diagonal with re-

spect to the bottom of the car-body, as illustrated in Figs. 1 and 2 of the drawings.

In order that the ratchet-toothed car-wheels may be locked on either side of the car, and that the wheels of the front and rear axles may be locked simultaneously by the one spray-bar, the ratchet-teeth on one of the rear wheels are constructed just the reverse of those on the other, and the same reverse construction is adopted with respect to the front wheels as is illustrated in the drawings.

Beneath the bar D friction-springs f may be applied for the purpose of retaining the bar in its locked or unlocked position.

15 Instead of the springs, the guide-bars f' may be bowed slightly, so as to act bindingly upon the bar D, or other suitable detents may be provided for the like purpose.

20 In Fig. 3 the ratchet-teeth are shown formed on the flange of the car-wheel, and this construction may answer a good purpose; but the construction shown in Figs. 1 and 2 is far preferable; and, in Figs. 4 and 5, pins are shown projecting from the inner faces of the car-wheels, and this construction may be found 25 preferable to either of the other constructions, as there will be great strength secured, and the pins can be cheaply applied to or cast upon the wheels.

30 In operating with the invention, the attendant lays hold of one or the other handle of the spray-bar and moves the bar horizontally on its pivot until the lugs come under the teeth shown in Figs. 1 and 2, or in contact with

the teeth shown in Fig. 3, or between the 35 pins shown in Figs. 1 and 5. This adjustment of the spray-bar instantly stops the revolution of the wheels, and the wheels slip with great resistance upon the inclined track or road, and the result is a gradual slackening 40 of the speed and final stoppage of the train. If it is not desired to stop the train entirely, the attendant moves the spray-bar at the proper time out of locking relation with the teeth or pins, which adjustment frees the 45 wheels and allows them to revolve, whereupon the speed of the train will become accelerated.

What I claim as my invention, and desire to secure by Letters Patent, is—

1. The combination of a horizontally-vibrating spray-bar provided with stop-lugs and applied upon a car, with car-wheels provided with spraying teeth or pins, substantially as and for the purpose described. 50

2. A vibrating spray-bar, in combination 55 with two pairs of car-wheels, each pair provided with reversely-constructed spraying-teeth, substantially as and for the purpose described.

3. The vibrating spray-bar provided with 60 stop-lugs and an extension handle or handles, substantially as and for the purpose described.

ANDREW A. SMITH.
